UNITED STATES PATENT OFFICE

2,478,339

LOCKING DEVICE FOR CLAMP SCREWS

Edmund R. Sullivan, Louisville, Ky.

Application January 30, 1947, Serial No. 725,248

4 Claims. (Cl. 70—230)

1

This invention relates to an improved locking device for clamp screws.

The principal object of the present invention is to provide an improved locking device adapted to be associated with the mounting bracket of any outboard motor for securely locking the bracket against removal and preventing the same from becoming loosened through motor vibration.

Another object is the provision of a locking device particularly adaptable for assemblage on the mounting bracket of a standard outboard motor and having novel means for automatically locking the bracket to a boat when the thumb screws thereof are screwed home.

A further object is to provide a locking device having a pawl and ratchet mechanism adapted to be actuated by a single lock to assure of the clamping screws of a mounting bracket being securely and readily locked in place.

These and other objects and advantages will be apparent as the following specification is considered with the accompanying drawings, wherein:

Figure 1 is a perspective view of the locking device assembled on an outboard motor mounting bracket;

Figure 2 is a plan view of the bracket and assembled locking device;

Figure 3 is a front elevation of the locking device with the cover plate removed, showing the pawls in locking positions relative to the ratchets;

Figure 4 is a similar view to Figure 3 but with the pawls in open or unlocked positions;

Figure 5 is a section on the line 5—5 of Figure 4;

Figure 6 is a section on the line 6—6 of Figure 4; and

Figure 7 is a section on the line 7—7 of Figure 3.

Referring more particularly to the drawings, wherein like reference characters designate similar parts throughout the several views, numeral 1 relates generally to an outboard motor attachment bracket assembled on a member 2 which may be the rear end board of a boat or a part of a storage rack for outboard motors. The bracket 1 includes two downwardly depending arms 3 which are enlarged and slotted at their lower ends, as at 4, to receive a headed bolt 5 which carries one-half of a clamping bracket 6 adapted to suitably engage with an outboard motor, not shown, so that the motor is swingably attached to the bracket in the usual manner. The bracket 1 is also formed with two downwardly bent yokes 7 having threaded apertures 8 adjacent their lower ends for receiving screw

2

threaded clamping screws 9 which are formed with object engaging elements 10, rotatably attached thereto. A spacing bolt or the like, not shown, is adapted to extend through apertures 11 in the upper ends of the yokes 7. A T-handle 12 slidably extends through the outer ends of each of the clamping screws 9 so that the latter may be rotated into clamping and unclamping positions in an obvious manner.

10 The locking mechanism is mounted in an elongated housing 13 of metal or other suitable material having a front wall 14 and a side wall 15 extending around the periphery thereof. The housing is closed by a rear wall 16 removably secured thereto by screws or the like 17. Spaced, aligned openings 18 and 19, formed in the walls 14 and 16, respectively, are adapted to accommodate the clamping screws 9. A casing 20 of a cylinder lock, operable by a key 21 and including 15 a lockable plug 22 having an eccentric portion 23 thereon, is suitably anchored in the housing 13 and projects through an opening 24 in the center of the front wall 14 thereof. The eccentric portion 23 extends between and cammingly 20 engages with arcuate recesses 27 and 28 formed in the respective lower and upper edges of a pair of spaced locking pawls 25 and 26. The pawls 25 and 26 are suitably pivotally connected at their 25 opposed inner ends to the housing 1 by pivots 29, and the free ends thereof are formed with curved ratchet engaging hook portions 30 adaptable to interengage with teeth 32 formed in ratchets 31 suitably keyed, as at 33, to each of the clamp screws 9. Springs 34, seated in recesses 35 and 36 formed in side wall 15 of the housing 1 and the respective upper and lower sides of the pawls 25 and 26 adjacent their free ends, serve to normally retain the hook portions 30 of the pawls in locking engagement with the ratchet teeth 32 in an obvious manner.

40 When it is desired to adjust the clamping screws 9 into clamping position relative to the end board 2 of the boat, the locking key 21 is left in the vertical or twelve o'clock position shown in Figure 1. In this position of the key, the eccentric portion 23 thereof will be in the Figure 4 position with respect to the upper and lower locking pawls 25 and 26 so that the hooked portions 30 thereof will be out of engagement with the ratchet teeth 32. Thus, the clamping screws may be freely 45 rotated in a clockwise direction, viewing Figure 1, into clamping engagement with the end board, or in the opposing direction to loosen or remove the clamps. To lock the screws 9 in such clamping positions, the key 21 is then rotated 90

degrees in a clockwise direction, also viewing Figure 1, or to a three o'clock position, so that the eccentric portion 23 thereof assumes the Figure 3 position. The tension of the springs 34 serve to force the pawls 25 and 26 downwardly and upwardly, respectively, until the hooked portions 30 thereof engage with the ratchet teeth 32. In this position of the key 21 and locking pawls 25 and 26, it will be apparent that the clamping screws 9 may not be rotated in an opposing or counter clockwise direction, viewing Figure 1, and will be retained in such a locked position and be prevented from becoming dislodged by motor vibration and the like. The key 21 will usually be removed when the clamp has been locked to prevent of the same becoming lost or the clamp being tampered with.

It will be understood that the housing 13 may readily be assembled and disassembled from the bracket 1 by removing the elements 10 and unscrewing the clamping screws 9. After the housing 13 has been removed from the bracket 1, the screws 9 may be removed therefrom by unscrewing the attaching screws 17 and loosening the rear wall 16 from the housing so that the screws 9 may be unscrewed, after first removing the handles 12.

While I have shown and described a preferred embodiment of my locking device, various changes and modifications may be made therein without departing from the scope and spirit of the appended claims.

Having thus described my invention what I claim is:

1. In combination with a clamp including clamping arms having apertures therein, a pair of spaced clamping rods extending through said apertures, a housing mounted on said rods, means on said rods for moving the same into and out of clamping engagement, spaced members pivoted at their opposing ends in said housing, means carried by said rods and arranged in said housing, the free ends of said pivoted members being adapted to engage said last mentioned means, and locking means in said housing between said pivoted members having cam means engageable with said members for actuating said members into and out of locking engagement with said rods.

2. In combination with a clamp including a pair of spaced clamping arms, having apertures therein, clamping screws threadedly extending through said apertures, a housing mounted on said screws, means on said screws for moving the

same into and out of clamping engagement, spaced pivoted members in said housing, toothed means carried by said screws and arranged in said housing, the free ends of said pivoted members being adapted to engage said toothed means, a locking means extending into said housing, cam means on said locking means engageable with said members for actuating said members into and out of locking engagement with the toothed means on said screws.

3. In combination with a clamp including a pair of spaced clamping arms having apertures therein, clamping screws threadedly extending through said apertures, a housing mounted on said screws, means on said screws for rotating the same, spaced members pivoted at their opposing inner ends in said housing, ratchet means carried by each of said screws and arranged in said housing, the free outer ends of said members being adapted to engage with said ratchets, a locking means extending into said housing, an eccentric on said locking means engageable with the sides of said members for actuating said members into and out of locking engagement with ratchet means on said screws.

4. In combination with a clamp including a clamping means having apertures therein, clamping screws threadedly extending through said apertures, a housing mounted on said screws, means on said screws for rotating the same, spaced pawl members pivoted at their opposing inner ends in said housing, ratchet means carried by and keyed to each of said screws and arranged in said housing, spring means engaging with each of said pawl members whereby the free outer ends of said members are adapted to engage with said ratchets, a locking means extending into said housing, an eccentric on said locking means engageable with grooves in the side edges of said members, and a key removably mounted in said locking means for rotating said eccentric and moving said pawl members out of locking engagement with said ratchets.

45 EDMUND R. SULLIVAN.
